(57) **CLAIM**

We claim the ornamental design for a multipurpose cutting tool, as shown and described.

DESCRIPTION

FIG. 1 is a perspective view of a multipurpose cutting tool according to our new design, shown in a closed configuration; FIG. 2 is a left side elevation view thereof; FIG. 3 is a right side elevation view thereof; FIG. 4 is a top plan view thereof; FIG. 5 is a bottom plan view thereto; FIG. 6 is a front elevation view thereof; FIG. 7 is a rear elevation view thereof; FIG. 8 is another perspective view thereof, shown in an open configuration; FIG. 9 is a left side elevation view thereof; FIG. 10 is a right side elevation view thereof; FIG. 11 is a top plan view thereof; FIG. 12 is a bottom plan view thereto; FIG. 13 is a front elevation view thereof; FIG. 14 is a rear elevation view thereof; FIG. 15 is another left side elevation view thereof, shown in another open configuration with a cutting tool extended; FIG. 16 is another left side elevation view thereof, shown in another open configuration; and, FIG. 17 is another left side elevation view thereof, shown in another closed configuration with a cutting tool extended. The broken lines immediately adjacent to the shaded areas represent bounds of the claimed design. The broken lines in the drawings illustrate portions of the multipurpose cutting tool that form no part of the claimed design.
